UNITED STATES PATENT OFFICE.

AARON HEISLER, OF PITTSBURGH, PENNSYLVANIA.

SAFETY APPLIANCE FOR CRANES.

1,315,495.

Specification of Letters Patent.

Patented Sept. 9, 1919.

Application filed May 2, 1919. Serial No. 294,175.

To all whom it may concern:

Be it known that I, AARON HEISLER, a citizen of the United States, residing at Pittsburgh, in the county of Allegheny and State 5 of Pennsylvania, have invented certain new and useful Improvements in Safety Appliances for Cranes, of which the following is a specification.

This invention relates to safety devices 10 used in connection with overhead traveling cranes; and it consists in the novel construction and combination of the parts herein-after fully described and claimed whereby the wheeled crane or crane structure is prevented from traveling too far upon its supporting rails.

In the drawings, Figure 1 is a side view of one end portion of a traveling crane provided with safety appliances according to 20 this invention. Fig. 2 is an end view of one end carriage showing the safety bumper. Fig. 3 is a detail side view of the brake on the driving shaft. Fig. 4 is a detail plan view of one of the resistance weights showing 25 its guide in cross-section. Fig. 5 is a detail side view of the bell-crank lever, and Fig. 6 is an end view of the same.

The crane is provided with a crane beam 2 of any approved construction, and generally comprising two girders, and its end portions are secured to two similar carriages 3 provided with wheels 4 which run on rails 5 secured on beams or other similar supports 6. Only one end portion of the crane beam 30 is shown as the other is similar to it in construction, and is supported in a similar manner. The lifting mechanism is carried by the crane beam 2, and is of any approved construction. In order to move the crane beam 40 and its carriages along the rails a driving shaft 7 is provided, and is journaled parallel to the crane beam in suitable bearings 8, and this shaft is operatively connected with one of the rail wheels 4. The driving shaft 7 is provided with a wheel 9 for revolving it, and it may be revolved by hand 45 or by power as found desirable.

In order to prevent the crane from being run too far along the rails, a brake wheel 10 is secured on the driving shaft 7, and the brake is operated automatically as herein-after described when the crane arrives at the end of its travel. The brake is formed of a pair of brake jaws 12 pivoted together by a pin 14 and provided with brake shoes 15 which bear on the wheel 10. A brake shaft

16 is provided and has two screwthreaded portions 17 and 18 which engage with the free end portions of the brake jaws, and which are arranged right and left so that the 60 wheel 10 may be gripped between the brake shoes or released from engagement with them. A toothed wheel 19 is secured on the shaft 16 for operating the brake.

A pneumatic brake cylinder 20 is secured 65 to the crane beam, and is provided with a piston 21 and a piston-rod 22. The piston-rod 22 is secured to a toothed rack 24 which gears into the toothed wheel 19. Compressed air is supplied to the cylinder from a reservoir 25 to which it is coupled by a pipe 26 connected to one end of the cylinder, and a pipe 28 connected to its other end. The pipe 26 has a valve 27, and the pipe 28 has a valve 29 for controlling the passage of air, but any 70 approved arrangement of valves may be used in carrying out this invention. Separate outlet valves 30 for air may also be attached to the ends of the cylinders. The reservoir 75 is supplied with compressed air by means 80 of any suitable air pump which is driven by a motor or by hand as found convenient.

A guide 32 is secured over the carriage 3 at one end portion of the crane, and 33 is a bumper slide which engages with the guide 85 32 and which projects in advance of one end of the said carriage.

A bumper 34 is secured on the free end portion of the slide, and is adapted to strike a wall, another crane, or any other object in 90 the path of the crane, so that the travel of the crane may be limited. A flexible connection, cord or cable 35 is secured to the slide 33 at one end, and is led over suitable guide sheaves 36 on the crane, and its other end is secured to the piston-rod 37 of an air cushioning cylinder 38 which is also secured to the crane beam. The air cylinder 38 has a piston 39, and a flexible connection, cord or cable 40 is attached to the other end of the 100 piston-rod 37, and is led over a suitable guide sheave 41 and has a resistance weight 42 secured to its free end.

The resistance weight 42 slides in a vertical guide 43 secured to the crane beam, and 105 44 and 45 are additional resistance weights which are picked up one after another by the weight 42 which is the lowest weight in the series. The weights 44 and 45 are normally supported by the guide 43, and they provide 110 a variable and increasing resistance when the flexible connection is operated.

A stop 46 is secured to the flexible connection 40, and 47 is a bell-crank lever pivoted to the crane beam by a pin 48 and having a forked arm 49 which is arranged in the path 5 of the stop 46. The other arm 53 of the bell-crank lever is connected by any suitable rod or cord 50 with a lever 51 on the valve 27 which admits compressed air to one end of the cylinder 20. When the bumper strikes 10 any stationary object, it pulls upon the flexible connections, raises the resistance weight and overcomes the resistance of the air in the cylinder 38, and opens the valve 27 by means of the bell-crank lever which is operated by the stop 46.

The compressed air thus admitted to the brake cylinder 20 applies the friction brake to the brake wheel on the driving shaft of the crane, and prevents the crane from traveling too far.

20 A cord 52 or other similar connection is also attached to the arm 49 of the bell-crank lever and is carried to the point from which the crane is operated, so that the arm 49 of 25 the bell-crank lever can be moved out of the path of the stop at will. The other arm of the bell-crank lever is connected to the arm 49 by a helical spring 54 and lugs 55 which overlap each other so that the arm 49 can be moved in one direction without operating the arm 53.

A similar cord or connection 56 is also secured to the lever 51 on the valve which when opened causes the brake to be applied, 35 and is also carried to the point from which the crane is operated, so that the valve can be opened by hand to apply the brake.

The valves on the air cylinders are of any 40 approved make and may be three-way inlet and outlet valves, so that the pistons can be moved in each direction at will. One end of the air cushioning cylinder 38 is also connected with the reservoir by a pipe 58 having a valve 59, so that the slide can be retracted 45 by air pressure if desired, and so that the pressure in the cushioning cylinder can be regulated.

What I claim is:

1. The combination, with a traveling crane 50 provided with a revoluble driving shaft, of a friction brake mechanism controlling the said driving shaft, a movable contact device carried by the crane, and intermediate actuating devices interposed between the contact device and the brake mechanism whereby the 55 brake is applied to check the revolution of the said driving shaft when the contact device is actuated.

2. The combination, with a traveling crane 60 provided with a revoluble driving shaft, of a friction brake mechanism controlling the said driving shaft, an air cylinder for operating the brake mechanism provided with an inlet valve for compressed air, a movable 65 contact device carried by the crane, and in-

termediate actuating devices interposed between the contact device and the said inlet valve whereby the valve is opened and the brake is applied to check the revolution of the said driving shaft when the contact device is actuated.

3. The combination, with a traveling crane provided with a driving shaft, of a guide carried by the crane, a bumper slide engaging with the said guide and projecting in 75 advance of the crane, a brake mechanism controlling the said driving shaft, an air brake cylinder provided with an inlet valve and operatively connected with the brake mechanism, a flexible connection attached 80 to the bumper slide and provided with a resistance which normally holds the said slide projected, and means for connecting the flexible connection with the said inlet valve so that the valve is opened to apply the 85 brake when the bumper slide is pressed back in its guide.

4. The combination, with a traveling crane provided with a driving shaft, of a bumper slide carried by the crane and projecting in 90 advance of it, a brake mechanism controlling the said driving shaft, an air brake device for operating the brake mechanism, a flexible connection operatively connected with the said air brake device and the bumper 95 slide, and an air cushioning cylinder provided with a piston which is connected to the said flexible connection.

5. The combination, with a traveling crane provided with a driving shaft, of a bumper 100 slide carried by the crane and projecting in advance of it, a brake mechanism controlling the said driving shaft, an air brake device for operating the brake mechanism, a flexible connection attached to the bumper slide 105 and provided with a resistance which normally holds the slide projected, a stop carried by the said flexible connection, and a pivoted bell-crank lever having one arm arranged in the path of the said stop and having its other arm operatively connected with the air brake device.

6. The combination, with a traveling crane provided with a driving shaft, of a bumper slide carried by the crane and projecting in 115 advance of it, a brake mechanism controlling the said driving shaft, an air brake device for operating the brake mechanism, a flexible connection attached to the bumper slide and provided with a resistance which normally holds the slide projected, a stop carried by the said flexible connection, and a pivoted bell-crank lever having one arm arranged in the path of the said stop and having its other arm operatively connected with 120 the air brake device, said bell-crank lever being formed of two spring-controlled arms provided with overlapping lugs which connect the arms positively in one direction and permit one arm to be moved out of the path 125 130

of the stop against the pressure of the spring without moving the other arm.

7. The combination, with a traveling crane provided with a driving shaft, of a bumper slide carried by the crane and projecting in advance of it, a brake mechanism controlling the said driving shaft, an air brake device for operating the brake mechanism, a flexible connection attached to the bumper slide, a variable resistance attached to the flexible connection and normally holding the bumper slide projected, said resistance increasing step by step as the bumper slide is pushed back, and means for operatively connecting the said flexible connection with the air brake device.

8. The combination, with a traveling crane

provided with a driving shaft, of a bumper slide carried by the crane and projecting in advance of it, a brake wheel secured on the driving shaft, pivoted brake jaws for engaging the brake wheel, a brake shaft provided with right and left screw threaded portions for operating the brake jaws, an air brake cylinder provided with a piston and piston-rod, a toothed rack and toothed wheel connecting the said piston-rod with the brake shaft, and means for operating the air brake cylinder to apply the brake when the said bumper slide is pushed back.

In testimony whereof I have affixed my signature.

AARON HEISLER.
